UNITED STATES PATENT OFFICE.

OLAUS OLSSON, OF BROOKLYN, NEW YORK, ASSIGNOR OF ONE-HALF TO
JOHAN A. JOHANSON, OF SAME PLACE.

GAME APPARATUS.

SPECIFICATION forming part of Letters Patent No. 529,802, dated November 27, 1894.

Application filed December 18, 1893. Serial No. 493,954. (No model.)

To all whom it may concern:

Be it known that I, OLAUS OLSSON, a subject of the King of Sweden and Norway, and a resident of Brooklyn, in the county of Kings 5 and State of New York, have invented certain new and useful Improvements in Game Apparatus, of which the following is a specification.

My invention consists of an improved arrangement of pivoted spring guns, with an inclosed field as the top of a table, pins to be set thereon for being knocked down, and grids at the ends of the field for reception of the balls shot from the guns in suitable relation with 15 numbers or marks posted for targets, to identify the number struck by the ball as herein-after fully described, reference being made to the accompanying drawings, in which—

Figure 1, is a perspective view of my improved game apparatus, and Fig. 2, is a detail in longitudinal section of the game on line $x-x$, Fig. 1, on an enlarged scale.

At each end of a table a , or other level plain bounded by vertical guards b , to prevent a 25 ball and other objects used on the table from rolling off, I mount a spring gun d , a little above the surface of the table and so as to turn on the pivot e , in the plane of the table for setting it in range with points anywhere along 30 the other end of the table, as the different numbers f , figured on the inside of the end guards b , and in front of these end guards I arrange the grids g , in the places of portions of the table top cut away, the bars of which 35 guides are spaced in uniformity with the spaces of the numbers f . At a suitable height above the guides but below the numbers I arrange flexible cushions h , one at each end against and partly under which the ball is 40 shot from the gun so as to roll along the bars of the guard for approaching the target num-

ber in its range and strike and lodge under the cushion and be retained on the bars of the guard so as to remain and identify the number struck for counting the game. On the intermediate field of the table I arrange spots as j , for placing pins as k , in any desired order for another feature of the play which may be counted alone or together with the count of the target numbers at the ends of the field. 45 The guns are affixed to blocks l , by which they are pivoted to the surface of the table and they project outward through the end guards b , for convenience in contracting the springs m , by pulling on the knobs n , said knobs being attached to rods o , extending through the breech into the bore and connected with a ram head p , between which and the breech the spring is suitably arranged for being retracted 55 when the knob is pulled back and for thrusting the ball when let go. A cushion q , in the breech and a collar s on the knob serve to relieve the force of the shocks of the recoil of the spring on the gun.

I claim—

The combination of the inclosed field, the pivoted spring guns at the ends of the fields, the grids at said ends the cushions on the guards back of and projecting over the grids at a suitable height for receiving the balls 70 under them and retaining them on the grids by pressure on the balls, and the target numbers on the grids, said grids being in advance of the guards having the target numbers substantially as described. 75

Signed at Brooklyn, in the county of Kings and State of New York, this 15th day of September, A. D. 1893.

OLAUS OLSSON.
